CONTROL SYSTEM

William K. Sonnemann, Roselle Park, N. J., assignor to Westinghouse Electric Corporation, East Pittsburgh, Pa., a corporation of Pennsylvania

Application April 30, 1945, Serial No. 591,079

7 Claims. (Cl. 171—119)

1

My present invention relates to phase-sequence filter-networks, for selectively responding to different phase-sequence components of a three-phase line-current or line-voltage, and to control-systems utilizing such filters.

My invention is an improvement upon the present knowledge of the art, with respect to sequence-filters, as represented in the sequence-filter diagrams and explanations given on pages 248 and 249 of the Electrical Transmission and Distribution Reference Book, 1942 edition, published by Westinghouse Electric & Manufacturing Company.

An object of my invention is accomplished by providing a sequence-filter which will respond to both the positive and negative phase-sequence components, and more specifically, a filter which responds strongly to the negative-sequence components of the impressed three-phase current or voltage, and only in a small degree to the positive-sequence component, or to the combined positive and zero-sequence components.

This large disproportionality of the responses to the positive and negative-sequence components is particularly important when the filter is utilized in a control-system for obtaining a relaying-response to different kinds of faults on a transmission-line, in response to different phase-sequence components of the three-phase line-current. Heretofore, the most successful relay-control scheme for responding, in one unit, to any of the different kinds of faults which are possible on a three-phase line, has been the type HCB or HKB system, utilizing a filter having an output-voltage which is responsive to the vectorial sum of the positive-sequence line-current, plus a suitably weighted response to the zero-sequence line-current, as set forth in a Harder Patent, 2,183,646, and as shown at (q) on page 249 of the above-mentioned reference book.

In spite of three major difficulties or shortcomings, the positive-plus-zero filter has enjoyed a long and widespread use, since its inception. One of its difficulties has been that the relative phase-positions of the positive and zero-sequence components of the line-current have been different, for faults on different phases, so that the absolute magnitude of the vectorial sum of these two components has been subject to variation, according to which phase was faulted, even considering faults which are of the same type, such as single-phase ground-faults, phase-to-phase faults, and double-phase-to-ground faults. Another difficulty has been its response to positive-sequence currents, necessitating a relay-set-

2

ting higher than the full-load current of the line, frequently resulting in insufficient sensitivity to single-phase or double-phase ground-faults, particularly in cases where the zero-sequence currents were relatively small.

Another possible objection to the positive-plus-zero-sequence-filter has been an objection, which is at least a theoretical possibility, that it is possible for the relay to have no response at all to certain phase-BC ground-faults in which the positive-sequence component and the weighted zero-sequence component might happen to be nearly equal and opposite in phase, so as to cancel out each other, in some particular transmission-system.

These difficulties are now avoided, in my present invention, by combining the positive and negative-sequence responses in a single filter, and by heavily weighting the negative-sequence response, as by making it, say, eight or nine times more sensitive than the positive-sequence response, so that a relay which is connected to the output-terminals of the filter will respond substantially only to the negative-sequence magnitude, for all kinds of faults where there is any negative-sequence current-component, and yet which will respond to balanced three-phase faults, which have only the positive-sequence current-component. Since three-phase faults are nearly always very severe faults, a fault-responsive relay does not, in general, need to have any great sensitivity in order to respond to such faults, whereas, for certain other types of faults, the fault-currents may be considerably smaller than the full-load line-current, as is well known, so that a considerable relay-sensitivity is required. An advantage of having the relay-voltage composed of eight or nine parts negative-sequence response, and one part positive-sequence response, is that the vectorial sum of these two responses does not change too much in dependence upon the relative phase of the positive-sequence component with respect to the negative-sequence component, according to which line-phase, or phases, are faulted, because the positive-sequence component is such a small percentage of the large negative-sequence component of the relay-voltage.

Heretofore, a double response to the positive and negative phase-sequence components of the line-current, heavily weighted in favor of the negative-sequence response, and excluding the zero-sequence response, has been impractical because of the necessity for utilizing two separate phase-sequence networks, one responding to the

positive-sequence current and the other responding to the negative-sequence current.

With the foregoing and other objects in view, my invention consists in the circuits, combinations, systems, apparatus, elements and methods hereinafter described and claimed and illustrated in the accompanying drawings, wherein:

Figure 1 is a diagrammatic view of an embodiment of my invention in the form of a sequence-filter for developing a single-phase output-voltage,

Figs. 2 and 3 are vector diagrams illustrating its response to positive-sequence inputs and negative-sequence inputs, respectively, and

Fig. 4 is a view similar to Fig. 1, showing how a zero-sequence response may be added, if desired.

In a positive-sequence system of vectors, $I_a = I_a e^{-j120}$ and $I_c = I_a e^{j120}$, the difference-current $(I_b - I_c) = 1.732 I_a e^{-j90}$. In the negative-sequence system, $I_a = I_a e^{j120}$ and $I_c = I_a e^{-j120}$, the difference-current $(I_b - I_c) = 1.732 I_a e^{j90}$, leading I_a instead of lagging behind I_a .

In a negative-sequence filter, having a single-phase output-voltage as shown in the Lenehan Patent 2,161,829, granted June 13, 1939, impedances $\dot{Z}_a$ and $\dot{Z}_b$ are used, traversed respectively by I_a and $(I_b - I_c)$; and the no-load or open-circuit output-voltage of the network is equal to the difference between the voltage-drops $I_a \dot{Z}_a$ and $(I_b - I_c) \dot{Z}_b$ in the two impedances $\dot{Z}_a$ and $\dot{Z}_b$. Since the network is to respond only to negative-sequence currents, its no-load output-voltage must be zero when positive-sequence currents are supplied to the network. This means that the magnitudes and relative impedance-phases of the impedances $\dot{Z}_a$ and $\dot{Z}_b$ are such that

$$I_a \dot{Z}_a = (I_b - I_c) \dot{Z}_b \quad (1)$$

for positive-sequence currents.

Putting

$$\dot{Z}_a = Z_a e^{j\alpha} \text{ and } \dot{Z}_b = Z_b e^{j\beta} \quad (2)$$

and substituting $1.732 I_a e^{-j90} = -j1.732 I_a$ for $(I_b - I_c)$, Equation 1 states, in effect, that

$$I_a Z_a e^{j\alpha} = 1.732 I_a Z_b e^{j(\beta-90)} \quad (3)$$

which means that

$$Z_b = 0.577 Z_a \quad (4)$$

and

$$90^\circ - \beta + \alpha = 0 \quad (5)$$

In a usual case, as shown in the Lenehan Patent 2,161,829, $\dot{Z}_a$ is a pure resistance, meaning that the impedance-angle $\alpha = 0$, and hence, from Equation 5, the other impedance-angle $\beta = 90^\circ$, thus defining $\dot{Z}_b$ as a pure inductive reactance such as a mutual reactance

$$\dot{Z}_b = Z_b e^{j90} = jZ_b = j0.577 Z_a$$

In accordance with my invention, I proportion the filter-impedances of a negative-sequence filter so that Equations 1 and 3 do not hold true, either because the two voltage-drops $I_a Z_a e^{j\alpha}$ and $1.732 I_a Z_b e^{j(\beta-90)}$ are not in phase with each other, or are of different magnitudes, or both. The output-voltage E_r of the phase-sequence network of said Lenehan Patent 2,161,829 is the difference between the two voltage-drops $I_a Z_a$ and $(I_b - I_c) \dot{Z}_b$, so that, if said voltage-drops are equal, as on positive-sequence energization, the output-voltage E_r is zero, whereas, on negative-

sequence energization, the second voltage-drop reverses, so that the output-voltage is

$$E_r = I_a Z_a e^{j\alpha} - 1.732 I_a Z_b e^{j(\beta-90)} = I_a Z_a e^{j\alpha} + 1.732 I_a Z_b e^{j(\beta-90)} \quad (6)$$

More specifically, it is an important feature of my present invention to make the difference between the two voltage-drops $[I_a \dot{Z}_a - (I_b - I_c) \dot{Z}_b]$ have a magnitude, such as one-eighth, or one-ninth, or other fraction, preferably a small fraction, of the magnitude of the sum of these voltage-drops, $[I_a \dot{Z}_a + (I_b - I_c) \dot{Z}_b]$. The effect of this design-arrangement is to make the filter predominantly a negative-sequence filter, so that the magnitude of its output-voltage is not greatly affected by the phase of the relatively small positive-sequence component, and yet providing a relay which is capable of responding to balanced three-phase faults, for example, which have no negative-sequence component. At the same time, the negative-sequence response enables the relay to remain unresponsive to the balanced three-phase load-currents of the line, because the line-current has no negative-sequence component, except when there is an unbalanced fault on the line, such as a single-phase fault, or a two-phase fault.

It is to be understood, of course, that my invention is of general application to negative-sequence filters of all descriptions, the basic general idea of my invention being to design the negative-sequence filter so that its output-voltage is not zero, when the filter is impressed with positive-sequence currents or voltages. More specifically, an important feature of my invention is to so choose the filter-constants, that is, the impedance-magnitudes and impedance phase-angles of the various filter-impedances, so that the filter-output, on positive-sequence energization, has a magnitude equal to one-eighth, or one-ninth, or other small fraction, say between one-fourth and one-twelfth, of the magnitude of the filter-output when impressed with a negative-sequence input of the same magnitude as the positive-sequence input.

These general principles of my invention are applicable to any of the sequence-filters which are shown on pages 248 and 249 of the above-mentioned reference book, or to any other sequence-filter which can be devised, the basic principle being to make the filter-output, as a result of positive-sequence energization, not zero, but a certain small fraction of the filter-output as a result of negative-sequence energization. The methods of calculation of the filter-performance, in terms of the various filter-impedances, are well understood, and are explained, for example, in the reference book citation.

In the illustrative filter-network shown in Fig. 1, the filter output-voltage E_r is equal to the difference of the voltage-drops as follows,

$$E_r = R_a I_a - jM(I_b - I_c) \quad (7)$$

where R_a is a resistance, traversed by the phase-A input-current I_a , said resistance being connected between the input-terminal m and the output-terminal n of the network. The output-terminal n is also the star-point connection for the three-phase input-currents I_a , I_b and I_c . The mutual reactance M is the reactance between the winding 1 and each of the windings 2 and 3 of a mutual-reactance device 1, 2, 3, having the windings 2 and 3 traversed, respectively, by

$\dot{I}_b$ and $-\dot{I}_c$. The reactance-winding 1 is connected between the network output-terminal p , and a point q , which is connected to the input-terminal m . The $3i_0$ return-point tap 4 on the resistance R_a is one-third of the resistance-ohms from n to m which has the result of cancelling out the zero-sequence response as will be seen from the following analysis.

The voltage-drop in the network-branch R_a is the voltage-drop from the point m to the point n in Fig. 1, which will be designated by the notation V_{mn} . From Fig. 1, remembering that the resistor-tap 4 is at the two-thirds point in the resistor R_a , it is evident that

$$V_{mn} = I_a (\frac{2}{3} R_a) - (\dot{I}_b + \dot{I}_c) (\frac{1}{3} R_a) \quad (8)$$

If we designate the positive, negative and zero phase-sequence components as $\dot{I}_{a1}$, $\dot{I}_{a2}$ and $\dot{I}_0$, respectively, then it follows, from the definitions of symmetrical coordinates, that

$$\left. \begin{aligned} \dot{I}_a &= \dot{I}_{a1} + \dot{I}_{a2} + \dot{I}_0 \\ \dot{I}_b &= a^2 \dot{I}_{a1} + a \dot{I}_{a2} + \dot{I}_0 \\ \dot{I}_c &= a \dot{I}_{a1} + a^2 \dot{I}_{a2} + \dot{I}_0 \end{aligned} \right\} \quad (9)$$

Substituting these values in Equation 8,

$$V_{mn} = \frac{1}{3} R_a \dot{I}_{a1} (2 - a^2 - a) + \frac{1}{3} R_a \dot{I}_{a2} (2 - a - a^2) + \frac{1}{3} R_a \dot{I}_0 (2 - 1 - 1) \quad (10)$$

thus eliminating the response to the zero-sequence component $\dot{I}_0$. But

$$1 + a + a^2 = 0 \quad (11)$$

and hence

$$2 - a - a^2 = 3 \quad (12)$$

$$\therefore V_{mn} = R_a (\dot{I}_{a1} + \dot{I}_{a2}) = R_a (I_a - \dot{I}_0) \quad (13)$$

Equation 10 shows that the two-thirds tap-point 4 on the resistor R_a eliminates the network-response to the zero-sequence current I_0 .

The result which is shown in Equation 13 could have been arrived at in another way from the equation

$$I_0 = \frac{1}{3} (I_a + \dot{I}_b + \dot{I}_c) \quad (14)$$

from which it will be seen that, in a system in which the zero-sequence current I_0 is either zero, or can be ignored, or regarded as being zero, because of Equation 10, then

$$I_a = -(\dot{I}_b + \dot{I}_c) \quad (15)$$

and Equation 8 instantly becomes

$$V_{mn} = I_a R_a \quad (16)$$

in a system in which the zero-sequence currents are absent or ineffective.

In the pure negative-sequence network, the value of the mutual reactance M is equal to $.577 R_a$, so that Equations 1 and 3 are satisfied. In accordance with my invention, the ratio of the mutual impedance M to the resistance R_a is not $.577$, but some other quantity, either real or imaginary, that is, either with or without a phase-angle. In particular embodiment of my invention shown in Fig. 1 and analyzed in Figs. 2 and 3, the ratio $M/R_a = .8 \times .577$, or $.462$, so that the output-voltage $E_r = V_{pn+}$, for positive-sequence inputs of a given magnitude, is one-ninth of the output voltage $E_r = V_{pn-}$ for a negative-sequence input of the same magnitude as the positive-sequence input. In other words, the mutual coupling between the windings 1 and 2, and between the windings 1 and 3, is $j0.462 R_a$, as indicated in Fig. 1.

In Fig. 2, it is assumed that the input-currents

$\dot{I}_a$, $\dot{I}_b$ and $\dot{I}_c$ have the positive-phase-sequence, so that the difference-current $(\dot{I}_b - \dot{I}_c)$ lags 90° behind $\dot{I}_a$, as shown. The voltage-drop $V_{mn} = R_a I_a$ is shown in Fig. 2 in phase with the phase-A current I_a . The voltage drop

$$V_{qp} = -V_{pq} = j0.462 R_a (\dot{I}_b - \dot{I}_c) = 0.462 \times 1.732 R_a I_a = 0.8 R_a I_a$$

as shown in Fig. 2; this voltage-drop being four-fifths as large as the voltage-drop V_{mn} because the value of the mutual impedance M is $.462 R_a$ instead of the value $.577 R_a$ which it would have in a pure negative-sequence network. This voltage-drop V_{qp} leads the difference-current vector $(\dot{I}_b - \dot{I}_c)$ by 90° , so that it is in phase with the voltage-drop V_{mn} . The terminal output-voltage of the sequence-filter or network is equal to $(V_{mn} - V_{qp})$, which is shown at V_{pn+} , the plus sign, in the subscript, indicating that it is the output-voltage for a positive-sequence current-input.

Fig. 3 shows the vector-conditions for the same magnitude of input-currents, but with the input-currents $\dot{I}_a$, $\dot{I}_b$, $\dot{I}_c$ having the negative phase-sequence, so that the difference-current $(\dot{I}_b - \dot{I}_c)$ leads the phase-A current I_a . The mutual-reactance voltage-drop V_{qp} leads the difference-current vector $(\dot{I}_b - \dot{I}_c)$ by 90° , as before, putting the reactance-voltage-drop V_{qp} in phase-opposition to the resistance-voltage-drop V_{mn} , so that the output-voltage V_{pn-} , which is equal to $(V_{mn} - V_{qp})$, or $(V_{mn} + V_{qp})$, is numerically equal to the sum of the magnitudes of the two voltage-drops, instead of being equal to their difference as in Fig. 2.

It is to be understood, of course, that an infinite number of other proportions are possible, the particular proportions which are illustrated in Figs. 1, 2 and 3 being intended merely as illustrative.

The total output-voltage $E_r = V$ of the network, when the impressed currents $\dot{I}_a$, $\dot{I}_b$ and $\dot{I}_c$ have both positive and negative-sequence components, is equal to the vector sum of the filter-responses to the individual sequence-components of the input-currents. The zero-sequence components of the input-currents have no effect upon the network shown in Fig. 1, because of the $\frac{1}{3}$ -point connection for the residual current $3i_0$. In the particular filter shown in Figs. 1, 2 and 3, these two output-voltage components V_{pn+} and V_{pn-} , for positive and negative-sequence inputs, respectively, are in phase with each other, only if the positive and negative-sequence input-components $\dot{I}_{a1}$ and $\dot{I}_{a2}$ are in phase with each other. Whatever the relative phase between these two filter-voltage components, V_{pn+} and V_{pn-} , the resultant output-voltage is the vectorial sum of the two.

An advantage of my invention is that one of these components, V_{pn+} , is quite small compared with the other component, V_{pn-} , in all cases except when the negative-sequence input-current component $\dot{I}_{a2}$ is quite small with respect to the positive-sequence input-current component $\dot{I}_{a1}$. Most relaying equipments (not shown) which may be connected to the output-terminals p and n of the filter-network, are either responsive to the magnitudes of the total or resultant filter-response E_r to both phase-sequences, or they are at least affected, in some way, by the phase and magnitude of the resultant filter-voltage, so that it is desirable for the magnitude of the resultant filter-voltage to be fairly constant, for faults occurring on different ones or combinations of the three line-current phases A, B and C.

Table (for Fig. 1)

I	II	III	IV	V	VI	VII	VIII	IX
Fault	I_{a1}	I_{a2}	ϕ	V_{pn+}	V_{pn-}	V	I	S
A-B-C	5	0	None	5	0	5	5	1.0
AB	2.88	2.88	-60	2.88	25.92	27.5	0.91	5.5
BC	2.88	2.88	180	2.88	25.92	23.0	1.09	4.6
CA	2.88	2.88	+60	2.88	25.92	27.5	0.91	5.5
A-G	1.67	1.67	0	1.67	15.03	16.7	1.5	3.3
B-G	1.67	1.67	-120	1.67	15.03	14.3	1.75	2.9
C-G	1.67	1.67	+120	1.67	15.03	14.3	1.75	2.9

The operation of the filter-network shown in Fig. 1 is indicated in Table 1, for different types of faults, such as a three-phase fault A-B-C, a phase-to-phase fault AB, BC, or CA, or a line-to-ground fault A-G, B-G, or C-G. Columns II and III indicate, respectively, the positive and negative-sequence current-components I_{a1} and I_{a2} , when the actual fault-current is 5 amperes. Column IV indicates the phase-angle ϕ of the positive-sequence component I_{a1} with respect to the negative-sequence component I_{a2} for the type of fault in question. Columns V and VI indicate the filter-voltage components V_{pn+} and V_{pn-} for the phase-sequence input-currents I_{a1} and I_{a2} , respectively, based on the particular design-constant, $M = .462R_a$, which has been described. Column VII indicates the magnitude or absolute value of the total filter output-voltage V, which is the vector sum of the components V_{pn+} and V_{pn-} , with the phase-angle ϕ between them. Column VIII indicates the line-amperes I which would be necessary to produce a filter-output voltage V of 5 volts. Column IX indicates the relative sensitivity S of the network-response to the various types of fault, taking the three-phase fault as a basis of comparison.

It will be seen, from the table, that the network of Fig. 1 is more sensitive to the unbalanced phase-to-phase faults AB, BC, CA, and to the single-phase ground-faults A-G, B-G, C-G, than to three-phase faults A-B-C, which is precisely what is desired, because the actual fault-currents which flow in the line-conductors, of a transmission-line, for example, have a tendency to be larger for three-phase faults than for single-phase faults.

The sensitivity for two-phase-to-ground faults has not been shown in the table. This is because the proportion of the negative-sequence current-strength I_{a2} to the positive-sequence current-strength I_{a1} , for such faults, depends upon the impedance of the zero-sequence network of the transmission-system under consideration, whereas, for all other types of faults, the positive and negative-sequence current-components I_{a1} and I_{a2} are equal, except in the case of the balanced three-phase fault, which has no negative-sequence component. Considering the conditions during a double ground fault, it is usually true that the zero-sequence impedance of the line is large, in proportion to the positive and negative-sequence impedances, which are about equal to each other, so that the sensitivity of my sequence-network to double ground faults would be somewhere intermediate between the values shown for the single ground faults and the ungrounded phase-faults, approaching the sensitivity for the phase-fault condition. In transmission systems where the zero-sequence impedance is quite low, the sensitivity of the filter-network of Fig. 1, to two-phase-to-ground faults, would approach that of the three-phase fault-condition. Again,

the operation of my filter-network is quite satisfactory.

Another important condition to be noted, in connection with the operation of the filter-network of Fig. 1, as shown in the table, is the relative insensitivity as to which phase is faulted, in the event of a fault involving less than all of the phase-conductors of the line. This is really a very advantageous condition, which has been a serious shortcoming of most previous networks for producing a single relaying voltage which is intended to be responsive to all different kinds of faults. This is accomplished by making the positive-sequence response small, as compared with the negative-sequence response, so that the unavoidable variations in the phase-angles between the positive and negative-sequence components will not make too much of a change in the magnitude of the total response, while, at the same time, having some positive-sequence response, so that the filter-system can respond insensitively to balanced three-phase faults.

Fig. 4 shows how any desired amount of zero-sequence response may be added to the response of Fig. 1, by adding a zero-sequence resistor R_0 , or, in general, any zero-sequence impedance $\dot{Z}_0$, connected between the star-point n' of the input-currents I_a , I_b , I_c , and the network output-terminal n , with the $3I_0$ return-circuit connected to any desired point $4'$, tapped off from the resistance R_0 . This change in the connections adds any amount of zero-sequence response, in the manner set forth in the previously mentioned Harder Patent 2,183,646, or in the network (q) of the reference book citation.

In operation, the network shown in Fig. 4 makes it possible to increase the sensitivity to ground faults, such as the faults A-G, B-G and C-G of the table. An important feature of the old type-HCB or HKB network, having only positive-sequence and zero-sequence responses, was its high ground-fault sensitivity, which was usually 8 times as great as its sensitivity to three-phase faults. In the first form of my new network, as shown in Fig. 1 and the table, using positive and negative-sequence responses, but no zero-sequence response, the ground-fault sensitivity was only about 3 times as great as its three-phase sensitivity, and if an attempt were made to increase the ground-fault sensitivity up to 8 times the three-phase sensitivity (by greatly decreasing the positive-sequence response, relatively to the negative-sequence response), then still higher phase-fault sensitivities would be obtained, which might cause trouble because of normally slightly unbalanced phase-to-phase loading, or because of other line-conditions.

The addition of the zero-sequence response, in Fig. 4, in addition to the positive-sequence and negative-sequence responses of Fig. 1, makes it possible to obtain any desired relative sensitivity to single ground-faults, while at the same time

using ratios considerably smaller than 8-to-1 or 9-to-1, for the ratio of negative-sequence to positive-sequence response, thus making the phase-fault sensitivity approach more closely toward the three-phase sensitivity. For example, if the three-phase sensitivity is again taken as unity, as in the last column of the table, it is possible, in Fig. 4, to obtain a sensitivity of 1.2 for AB and CA faults, and 1.9 for BC faults, while different tap-settings on the zero-sequence resistor R_0 provide ground-fault sensitivities of 4, or 8, or any other desired value, with only slight variations depending upon which phase is faulted. This is only an illustration.

At the same time, the presence of responses to all three of the phase-sequence components, in Fig. 4, enormously reduces the possibility or likelihood of all three components so nearly neutralizing each other as to have any difficulty in responding to BC double ground faults, as has sometimes been suspected in the case of the older type-HCB or HKB network.

By providing a tap 5 on the reactance-winding 1 in Fig. 4, it is readily possible to change the ratio of negative-sequence to positive-sequence response, making this ratio have any of several available values corresponding to the number of tap-positions provided. At the same time, the amount of zero-sequence response can be adjusted by means of the tap 4' on the zero-sequence resistor R_0 ; or the zero-sequence response can be cut out entirely by using the one-third-point tap 4 on the phase-A resistor R_A , as in Fig. 1. The embodiment of my invention, shown in Fig. 4, is thus quite versatile.

A network such as shown in Fig. 4 might also be necessitated for some special application, such as detecting a two-phase-to-ground fault on the star side of a delta-star transformer-bank at the far end of a long transmission-line (not shown). In such a case, the impedance of the equivalent zero-sequence network of the transmission system will be relatively low, meaning that the zero-sequence current-component will be large, while the negative sequence current-component will be very small, and the postulated long length of the transmission-line means that the fault-current will necessarily be small. Because of the smallness of the negative-sequence component, the response of my Fig. 1 filter to such a fault will approach the sensitivity for three-phase faults, which is not very great, because of the smallness of my positive-sequence response; and in the case of a long line, this degree of sensitivity to the positive-sequence current-components probably would not be adequate, without the addition of the zero-sequence response, such as is obtainable in Fig. 4.

While I have illustrated my invention in two different forms of embodiment, I desire it to be understood that such illustration is only illustrative, and by no means limiting, as to the applicability of my invention to different types of networks. Some of the general principles of construction and application have been set forth in the foregoing description, and other applications of the principles of my invention will be obvious from the description which I have given. I desire, therefore, that the appended claims shall be accorded the broadest construction consistent with their language.

I claim as my invention:

1. A phase-sequence-current filter-network for selectively responding to a plurality of phase-sequence components of an impressed three-phase

current, said filter-network comprising, in effect, two-impedances, $\dot{Z}_a = Z_a e^{j\alpha}$, and $\dot{Z}_b = Z_b e^{j\beta}$, circuit-connections for causing the impedance $\dot{Z}_a$ to be traversed, in effect, by any one of the phases of the impressed current, and for causing the impedance $\dot{Z}_b$ to be impressed, in effect, by the difference between the other two phases of the impressed current, and circuit-connections in effect serially connecting said impedances for producing an output-voltage responsive to the difference between the two voltage-drops thus produced, characterized by the impedance $Z_a e^{j\alpha}$ having a vector-value substantially different from

$$1.732 Z_b e^{j(b-90^\circ)}$$

2. A phase-sequence-current filter-network having a resistor, a three-winding mutual reactance device, input-terminals for an impressed three-phase current, output-terminals for a single-phase output-voltage, circuit-connections for energizing said resistor and two of the windings of said mutual reactance device in star-circuit connection from the several phases of the impressed current, and circuit-connections for energizing said output-terminals from a circuit serially including said resistor and the third winding of said mutual reactance device, characterized by said mutual reactance having a value substantially different from .577 times the value of the resistance.

3. The invention as defined in claim 2, in combination with a return-point tap-connection on said resistance at a point one-third of the resistance, measured from the star-point, for cancelling out the zero-sequence response.

4. The invention as defined in claim 2, in combination with a zero-sequence impedance traversed by the zero-sequence current flowing from said star-point, the output-circuit connections including said zero-sequence impedance.

5. A negative-plus-zero phase-sequence current-segregating filter-network for selectively responding to a desirably weighted vectorial sum of the negative and zero phase-sequence components of an impressed three-phase current, said filter-network comprising a plurality of impedances, in different phases, with the impedances so proportioned that the output-voltage of the filter-network has a relatively large value when the impressed three-phase current has no phase-sequence components other than the negative phase-sequence, and so proportioned that the output-voltage of the filter-network has a relatively small, but substantial, value when the impressed three-phase current has no phase-sequence components other than the zero phase-sequence, and so proportioned that the output-voltage of the filter-network has a relatively small, but substantial, value when the impressed three-phase current has no phase-sequence components other than the positive phase-sequence.

6. A phase-sequence-current filter-network for selectively responding to a plurality of phase-sequence components of an impressed three-phase current, said filter-network comprising, in effect, three impedances, $\dot{Z}_a = Z_a e^{j\alpha}$, $\dot{Z}_b = Z_b e^{j\beta}$, and $\dot{Z}_0$, circuit-connections for causing the impedance $\dot{Z}_a$ to be traversed, in effect, by any one of the phases of the impressed current, and for causing the impedance $\dot{Z}_b$ to be impressed, in effect, by the difference between the other two phases of the impressed current, and for causing the impedance $\dot{Z}_0$ to be traversed by the zero-sequence current, and circuit-connections in effect serially

connecting said impedances for producing an output-voltage responsive to the vectorial sum of the three voltage-drops thus produced, characterized by the impedance Z_{ae}^{1a} having a vector-value substantially different from $1.732Z_{be}e^{(b-90^\circ)}$.

7. The invention as defined in claim 1, characterized by the magnitude of the vector-difference between $I_aZ_{ae}^{1a}$ and $1.732I_aZ_{be}e^{(b-90^\circ)}$ being relatively small as compared to the magnitude of the vector-difference between $I_aZ_{ae}^{1a}$ and $1.732I_aZ_{be}e^{(b+90^\circ)}$, for any value of the impressed phase-A current I_a .

WILLIAM K. SONNEMANN.
